UNITED STATES PATENT OFFICE.

HENRY H. CUMMINGS, OF MALDEN, ASSIGNOR TO THE UNION BUTTON SEWING MACHINE COMPANY, OF BOSTON, MASSACHUSETTS.

BUTTON-SEWING MACHINE.

SPECIFICATION forming part of Letters Patent No. 398,586, dated February 26, 1889.

Application filed December 21, 1886. Serial No. 222,168. (No model.)

To all whom it may concern:

Be it known that I, HENRY H. CUMMINGS, of Malden, county of Middlesex, and State of Massachusetts, have invented an Improvement in Button-Sewing Machines, of which the following description, in connection with the accompanying drawings, is a specification, like letters on the drawings representing like parts.

10 In another application, Serial No. 222,165, filed by me on the 21st day of December, 1886, I have shown and described an apparatus or attachment in connection with a sewing-machine, whereby a button having four eyes may 15 be stitched either automatically across the eye of the button or from eye to eye in succession around the buttons.

In my present invention the apparatus for moving the button is so actuated that the 20 stitches for attaching the button to a fabric or other article are parallel, there being two lines of stitches rather than four, as will be described.

In the invention herein to be described the 25 button is held in a button-holder or foot mounted upon the end of a slide-rod fitted loosely within a carrier-bar substantially such as shown in my said application, the said rod having combined with it suitable mechanism whereby the rod is retained within the 30 carrier, while the needle is made to descend alternately through one and the other of two holes in the button, and the proper number of stitches having been taken, usually half the 35 number required to secure the button to the fabric, the said rod is released, so that a suitable spring, or equivalent, causes the rod and its attached button-holder or foot to be moved toward the operator to bring into position 40 under the needle another hole of the button, and thereafter the carrier-bar is vibrated, as before, while the needle descends alternately through one and then the other of the last two holes of the button, forming a series of stitches 45 parallel to those first made through the button. The lifting of the carrier-bar to provide for the insertion of a button forces the rod carrying the button-holder or foot into the carrier-bar, where it is held automatically. 50 One-half the number of stitches required to secure the button in place, or substantially

one-half, having been made, the latch which holds back the slide-rod and button-holder or foot is automatically released by a mechanism which will be hereinafter described, and 55 as soon as the required number of stitches to secure the button in place has been made the rotation of the main shaft of the machine is automatically stopped.

In the drawings, Figure 1 represents in plan 60 view the forward portion of the bed-plate of a sewing-machine having the main parts of my improved attachment applied thereto in working position. Fig. 2 is an under side view of the greater part of a sewing-machine 65 to which my invention is supposed to be applied, the said figure showing the novel devices which have been added to the machine to effect the release of the slide-rod and button-holder or foot when a button 70 has been partially stitched in position, also the means employed for stopping the rotation of the main shaft of the machine when the button has been fully stitched. Fig. 2^a is a detail view to show the meeting beveled 75 ends of the slide-bar *p*⁶ and of the finger 47. Fig. 3 is a front or left-hand end view of the parts shown in Fig. 1, with the upper portion of the machine added chiefly to show the needle-bar, the usual crank to operate it, and the 80 presser-rod which acts to hold the carrier-bar and foot down in position to retain the button close to the fabric while the button is being stitched. Fig. 4 is a section of Fig. 2 in the line *x* *x*, looking toward the right, the bed-plate being, however, turned over and shown as right side up. Fig. 5 is a longitudinal section of Fig. 2 in the line *x'*, looking toward the rear side of the machine. Fig. 5^a is a detail view to show the detent *r* for the slide-bar. Fig. 6 is a section of Fig. 5 in the dotted line *x'*². Fig. 7 is a detail showing the button-holder or foot and part of the carrier-bar with the rod therein. Fig. 8 is a side elevation of the foot or toe of the lifting-lever.

95 The bed-plate *A*, the main shaft *A'*, the link *a'*, actuated by an eccentric on the said shaft, the stud *a*², the crank *a*³, fast on the rock-shaft *a*⁴, the bearings *a*⁵ and *a*⁷ for the said shaft, the sector *c*⁸, the bevel-gear *c*⁷, the pawl *c*⁴, the pawl-carrier *c*⁶, the stud *a*⁹, the nut *a*¹⁰, the collar *c*, the eccentric *c*² therein, the carrier-

bar b^4 , pointed screws c' , by which to pivot the forked end of the said carrier-bar to the said collar, the pivoted guide b^3 , the bracket b^x , to hold it, the base a^2 of the attachment or apparatus, the screws or bolts b , to attach it to the bed-plate A , the latch b^8 , the button-holder or foot b^7 , held by it, the spring b^9 , to lock the said latch b^8 , the lever B^3 , having the rod B^6 , the worm d^2 , the worm-gear d' , the bolt d^5 , upon which it is mounted, the finger B^7 , fast upon the hub of the gear d' , the slide-rod 19 , its attached projection 18 , the stud m , the projection m' , the presser-bar A^7 , the needle-bar-actuating shaft A^6 , its link A^5 , the bearings A^8 for it and for the needle-bar A^4 , having the needle b^{12} , the cam-hub A^2 , the arm f , having its latch or dog f' , the belt-pulley C , loose on the shaft A' , the pin or projection e , extended from one side of the said pulley, the dog e' , to engage the said pin or projection, the hub e^3 , to which the said dog is pivoted, the spring e^4 , to act upon the said dog, and a shipper-lever, 22 , as well as the spring 23 , are all substantially as in my said application, and so need not be herein specifically described.

Herein the carrier-bar b^4 is bored from its outer end to receive a rod, h , provided at its front end with a screw-thread, h' , upon which is screwed a nut, h^2 , which enters a hole in a shank of the button-holder or foot b^7 , the latter having springs b^{13} b^{14} , and suitable slots to hold buttons of two different sizes, the shank of the said nut forming the pivot for the button-holder or foot as it is turned into one or the other of its two positions to be held by the latch b^8 .

The end of the carrier-bar b^4 nearest the operator is embraced by a bifurcated head, h^4 , which surrounds the screw-threaded portion h' of the rod h , and is interposed between the end of the carrier-bar and the rear side of the button-holder or foot, as best shown in Figs. 3 and 7.

The slide-rod h has fastened upon it between its ends by a set-screw, n , a stud, n' , which, extended through a horizontal slot in the carrier-bar, has attached to it by a screw, n^2 , a rod-holding latch, n^3 , the said latch having (see Fig. 1) a shoulder or projection to engage a pin or projection, n^4 , attached to the outer side of the carrier-bar b^4 , the said latch when engaged with the said pin or projection n^4 , as in Figs. 1 and 3, causing the rod h to be held back in the carrier-bar b^4 , compressing the spring n^5 . (See Fig. 7.) In this condition of the parts the vibration of the carrier-bar by an intermitting but semi-rotation of the eccentric c^2 will so move the button-holder or foot as to permit the needle b^{12} to descend first through the hole 33 and then through the hole 34 in the button, thus forming between them a series of stitches, as 35 , and the proper number of stitches, as 35 , having been made the latch n^3 is released by the action of a suitable latch-releasing device, o , to be described, which permits the spring n^5 , acting upon the rod h , to throw it forward in

the direction of the arrow thereon in Fig. 7, placing the hole 36 in the button (see Fig. 1) in position to be entered by the needle b^{12} , and thereafter as the carrier-bar b^4 is vibrated by the eccentric c^2 the needle will be caused to enter the hole 37 , and then again the hole 36 , until a certain number of stitches have been made through or from one to the other of the said holes making stitches parallel to the stitches 35 , and a sufficient number of stitches having been made to secure the button to the fabric or other article upon which it is to be stitched the rotation of the shaft A' is stopped, as will be described, and the lever o' will have its outer end depressed, which will cause the beveled toe o^2 , adjustably connected to it by the screw o^3 , to act against the stud n' and force the rod h back into the carrier-bar, compressing the spring n^5 and enabling the projection of the latch n^3 to again engage the projection n^4 of the carrier-bar.

The latch-releasing device o has its shank inserted into a split portion of the lever B^3 , where it is adjustably clamped by the clamp-screw o^4 . (See Fig. 3.) This lever B^3 is pivoted at o^5 , (see Fig. 1,) and the projection B^6 at its rear end (shown only in Fig. 2) is struck by the projection B^7 when substantially half the number of stitches needed to secure the button in place has been made, the movement of the lever B^3 , actuated by the projection B^7 , causing the releasing device o to be moved in such direction as to carry the outer end of the latch n^3 away from the carrier-bar b^4 .

The bed-plate and shaft A' , as well as the cam A^2 , are common to the Wheeler & Wilson sewing-machine, style No. 10, I having selected that form of machine with which to illustrate one practical embodiment of my present invention.

In practice the cam A^2 will actuate the usual take-up, and in addition thereto the groove of the said cam, as herein provided for, will receive in it a cam-block, p , carried at the end of a ball-like stud, p' , made adjustable in the end of a pawl-carrier, p^2 , having its fulcrum at p^3 , the said pawl-carrier having attached to it a pawl, p^4 , acted upon by a spring, p^5 ; the spring normally keeping the free end of the pawl in engagement with the teeth of a slide-bar, p^6 , arranged between suitable guides at the lower side of the bed-plate, the said slide-bar being normally held back against an adjustable stop, p^7 , by a spiral spring, 40 , attached to the slide-bar and to a stationary part of the machine.

The number of teeth in the slide-bar p^6 equals the maximum number of stitches to be made when attaching any one button; but the machine may be stopped before it has made the maximum number of stitches, provided the backward throw of the toothed slide-bar is arrested sooner or later by the stop p^7 .

Directly underneath the pawl p^4 , when at its backward throw, is pivoted a detent, r , (see Fig. 5,) it being of the same shape as the

pawl, and being acted upon by a spring, r' , (see Fig. 5.) which normally keeps the free end of the detent in engagement with the teeth of the toothed slide p^6 , the detent acting to prevent any backward movement of the toothed slide p^6 until after such time as the button shall have been fully stitched, at which time the said detent is released, and at the same time the pawl is released, as will be described, to permit the spring 40 to pull the toothed slide p^6 back against the stop p^7 .

The guide-block in which the slide-bar p^6 is moved is marked P, and it consists, essentially, of a bar of metal grooved for the reception of the slide-bar, the guide being secured to the under side of the bed-plate by suitable bolts, one of which is shown at p^{10} . The front end of the slide-bar p^6 is beveled, as shown at 42, Fig. 2, the bevel starting from the lower side of the bar and inclining upward toward the left-hand end of the machine.

The slide-bar p^6 , when in its most forward position, is retained in the groove of the guide-block P by a plate, 43, which is attached to the guide-block P by screws 44.

The guide-block P receives in it a short rock-shaft, 45, to one end of which is attached an angular arm, 46, (see Figs. 2 and 6,) the said arm having attached to it in the path of movement of the slide-bar p^6 a bevel-finger, 47, which, when the inclined portion 42 of the slide-bar p^6 meets the said finger, causes the arm 46 to be depressed slightly, or for a distance far enough to enable a shoulder, 48, (see Fig. 6,) on the said arm to be lowered below and so as to release the shipper-lever 22, so that the latter under the action of the spring 23, attached to a portion of the slide-rod 19, will cause the shipper-lever 40 to be moved about its pivot or fulcrum 48. During this movement of the shipper-lever, it acting upon the inclined bridge of the arm 46, causes the rock-shaft 45 to be turned far enough to cause a finger, 49, forming part of a collar, (see Fig. 6,) attached to the rock-shaft 45 by a screw, 50, to act against one end of the pawl-disengager 52, pivoted at 53 on the guide-block P, thus turning the said pawl-disengager far enough to remove both the pawl p^4 and the detent r from the slide-bar p^6 .

The movement described as given to the shipper-lever 22 by the spring 23 and rod 19 throws the inner curved end (see Figs. 2 and 4) of the said shipper-lever into position to strike the dog e' and release it from the pin or projection e of the belt-pulley C, thus enabling the latter pulley to run loose on the shaft A', and immediately thereafter the arm f, before described, and common to my said application, in its rotation will engage the shipper-lever, and the said arm f, being fast to the shaft A', will immediately stop the rotation of the said shaft.

The bifurcated head h^4 is of sufficient width 65 to act as a guide when the rod h is released, and also to maintain the button-holder or foot in proper position.

The guide-block P (see Fig. 2) is shown as provided with a scale, 56, showing numbers from eight to twenty-three, the said numbers 70 designating the minimum and maximum number of stitches to be made when stitching the button to a piece of fabric or other article.

The stop p^7 may be adjusted opposite any 75 one of the numbers referred to, and when in that position such number will designate the maximum number of stitches which may be made in a button before the machine will be stopped automatically. The spring 88, Fig. 80 5, normally acts to keep the arm 46 lifted.

From the foregoing it will be apparent that the machine will be automatically stopped when the beveled end 42 of the notched slide-bar p^6 strikes the beveled finger 47 on the 85 arm 46 of the rock-shaft 45. The said notched slide-bar is moved forward to the extent of one tooth or notch at each rotation of the hook-shaft A', or at each stitch made by the machine, the said slide-bar being thus fed forward by the pawl p^4 on the lever or pawl-carrier p^2 , and the latter being operated by the take-up cam A², secured to the said hook-shaft, and into the groove of which extends the block-finger p' on the end of the said lever or 90 pawl-carrier p^2 . It will be apparent that the number of stitches which will be made before the machine is stopped will be governed by the adjustment of the slide-bar stop p^7 , the said slide-bar being retracted until it comes 100 in contact with said stop by the spring 40, when the pawl p^4 and the detent r have been removed from the teeth of the slide-bar by the pawl-disengager 52, operated by the finger 49 of the rock-shaft 45, as hereinbefore described, 105 and the said pawl-disengager being operated simultaneously with the shipper-lever 22, by which the machine is stopped.

I claim—

1. The carrier-bar, means to vibrate it, the 110 rod h , and the button-holder or foot connected therewith, combined with a latch and a projection to retain the button-holder or foot in locked position with relation to the said carrier during the partial stitching of the button 115 in place, and with means to release the said latch and move the rod with its attached foot longitudinally with relation to the carrier-bar, substantially as described.

2. The carrier-bar, means to vibrate it 120 intermittently, the button-holder or foot, its attached rod free to be moved longitudinally with relation to the carrier-bar, and the head to act as a guide, combined with means to hold the rod in locked position with relation to 125 the said carrier-bar to retain the button-holder or foot in proper position while part of the button is being stitched, and with means to release the said rod from its locked position and move it with its attached foot longitudinally with relation to the carrier-bar, substantially as described.

3. In a button-sewing machine, the combination, with the shaft A', the cam A² there-

on, the pawl-carrier p^2 , actuated by the said cam, the pawl p^4 , pivoted to said carrier, the toothed slide-bar p^6 , having the beveled end 42, a detent for said slide-bar, the rock-shaft 45, having the finger 49, said shaft having also an arm, 46, provided with the finger 47, the disengaging-lever 52, the shipper-lever 22, its actuating-spring, the loose pulley C, and detachable connections between said pulley and the shaft A', substantially as set forth.

4. In a sewing-machine, the shaft A', the loose pulley C, detachable connections between said pulley and shaft, the shipper-lever 22, the notched and inclined arm 46, to hold the said shipper-lever, the rock-shaft 45, its attached finger 49, the pawl-disengaging lever

52, the pawl-carrier p^2 , its attached pawl and the detent, and means to move the pawl-carrier, combined with the toothed slide p^6 , moved intermittently by the pawl of the pawl-carrier and adapted to operate the inclined and notched arm to release the shipper-lever, and means to move the shipper-lever to enable it to continue the movement of the said inclined arm, to operate substantially as described. 20 25

In testimony whereof I have signed my name to this specification in the presence of two subscribing witnesses.

HENRY H. CUMMINGS.
